E. P. STEVENS.
LOCOMOTIVE ARCH CONSTRUCTION.
APPLICATION FILED FEB. 10, 1916.

Patented June 12, 1917.

Attest:

UNITED STATES PATENT OFFICE.

ENOCH P. STEVENS, OF CHICAGO, ILLINOIS, ASSIGNOR TO AMERICAN ARCH COMPANY,
OF NEW YORK, N. Y., A CORPORATION OF DELAWARE.

LOCOMOTIVE-ARCH CONSTRUCTION.

1,229,384.

Specification of Letters Patent. Patented June 12, 1917.

Application filed February 10, 1916. Serial No. 77,517.

To all whom it may concern:

Be it known that I, ENOCH P. STEVENS, a citizen of the United States, residing at Chicago, in the county of Cook and State 5 of Illinois, have invented certain new and useful Improvements in Locomotive-Arch Constructions, of which the following is a specification.

My invention relates to arch constructions for locomotive fireboxes and has special reference to improvements in the construction and arrangement of the marginal bricks of such arches.

A marginal brick occupies the space between the outermost water circulating arch tube and the adjacent side sheet of the firebox. Even in a single firebox the distance between the arch tube and the side sheet varies from end to end of the box. It has been the practice to install marginal bricks upon the tube and against the side sheet and to compensate for the varying distance between the side sheet and arch tube by the use of bricks of different lengths at the 20 different points. And likewise, it has been necessary to employ marginal bricks of different lengths in different fireboxes.

It is desirable to limit the number of sizes or patterns of marginal bricks which 25 are required to construct arches in the differing fireboxes of locomotives. With this end in view I have devised, and my invention consists in, an arch construction in which I employ main marginal bricks of 30 a single pattern long enough to co-act with a side sheet when the same is at the normal or most usual distance from the support of the inner end of the brick, in combination with a compensating or spacing key which 35 enables the marginal brick to be used when the spacing between its support and the side sheet is greater than said normal distance.

My invention will be readily understood on reference to the drawings that form part of this specification, and in which Figure 1 is a vertical transverse section of a locomotive firebox containing my invention; Fig. 2 is an enlarged view depicting a side sheet, an arch tube and my novel marginal bricks; Fig. 3 is a plan view thereof; and Fig. 4 illustrates a simplified form of the invention.

Further referring to the drawings, 2 and

2^a represent one of the side sheets of a 55 locomotive firebox;—3, 3^a are the outermost arch tubes;—and 4, 4 the intermediate arch tubes. It will be understood that these arch tubes are in substantial parallelism with the side sheet, longitudinally of the firebox. It 60 will also be understood that the arch tubes are inclined forwardly and downwardly in the firebox.

The body-bricks, a, of the arch may be of any suitable design adapted to cause 65 them to firmly retain their positions upon the arch tubes. The inner ends of the marginal bricks, b, may be likewise variously formed, according to the shapes of their supports. I prefer that each marginal brick 70 shall be socketed upon an arch tube as shown; in other words, in direct abutment with the tube, rather than with the end of a body brick.

In Fig. 1 I have shown a condition, 75 which, though not usual, is nevertheless frequently encountered in locomotive fireboxes. One arch tube (3^a) is near enough to its side sheet (2^a) to allow the use of a marginal brick, b, of standard or most common length; while the other tube (3) is so far from the side sheet (2) that a marginal brick, b, of standard length can find no direct support upon the adjacent side sheet. This condition calls forth and is typical of 80 my invention. Rather than substitute a longer marginal brick, I use a standard brick, b, and a smaller supplementary key brick, c, which latter rests against the side sheet of the firebox and provides a support 85 or abutment by which the brick, b, is held 90 in its proper inclined position.

The key brick, c, is wedge shaped; to the end that the same and a brick, b, may be adjusted to marginal spaces of different 95 widths. All of the key bricks so used in an arch may be of one pattern or size. Each has a straight edged back, c', which bears against the side sheet of the firebox. The inner edge of the key brick which forms the 100 abutment for the outer end on brick, b, may be either plainly inclined, as shown at c² in Fig. 4, or may be stepped, as shown at c³ in Fig. 2. I prefer the steps, c³, as they provide a surer support and engagement for 105 the outer end of the brick, b. There may be two or more of the steps, c³, according to the number of variations to be accommo-

dated. The back of the brick, *c*, is preferably channelled (see *c*⁴) to reduce the extent of its bearing on the side sheet and to avoid contact with the ends of the side sheet stay bolts (not shown). The inner surface of the key (*c*² or *c*³) contains a vertical groove or grooves, *c*⁵, which substantially conforms to the more or less pointed end, *b*², of the main brick, *b*. By this engagement, the 10 bricks *b* and *c* are interlocked and the dislodgment or disarrangement of the key brick is prevented.

By the use of bricks of the two patterns, *b* and *c*, the margins of a refractory arch 16 may be easily and quickly constructed in practically any firebox which contains arch supporting tubes.

Having thus described my invention, I claim as new and desire to secure by Letters 20 Patent:—

1. The improvement herein described comprising the side sheet and an arch tube of a locomotive firebox, in combination with a main marginal brick extending from said tube toward said side sheet, and a substantially wedge shaped key brick interposed between the end of said main brick and said side sheet and forming the abutment for the outer end of said main brick.

2. The improvement herein described comprising the side sheet and an arch tube of a locomotive firebox, in combination with a marginal brick extending from said tube toward said side sheet, and a substantially wedge shaped key brick interposed between the end of said main brick and said side sheet and forming the abutment for the outer end of said main brick.

ting portions of said bricks being interlocked, substantially as described. 40

3. The improvement herein described comprising the side sheet and arch tube of a locomotive firebox, in combination with a main marginal brick extending from said tube toward said side sheet, and a substantially wedge shaped, stepped, adjustable key brick interposed between the end of said main brick and said side sheet and forming the abutment for the outer end of said main brick. 45

4. The improvement herein described comprising the side sheet and arch tube of a locomotive firebox, in combination with a main marginal brick extending from said tube toward said side sheet, and a substantially wedge shaped, stepped, adjustable key brick interposed between the end of said main brick and said side sheet and forming the abutment for the outer end of said main brick and the abutting portions of said 50 bricks being interlocked, substantially as described.

5. A marginal arch brick supplement, comprising a substantially wedge shaped, stepped key brick, having an interlocking groove in its brick abutment face, substantially as described. 55

6. A marginal arch brick supplement, comprising a substantially wedge shaped, stepped key brick, having an interlocking groove in its brick abutment face, and having a channeled back, substantially as described. 70

In testimony whereof, I have hereunto set my hand this 8th day of January, 1916.

ENOCH P. STEVENS.
